UNITED STATES PATENT OFFICE

2,576,582

SCOOTER STARTER UNIT

Floyd A. Elliott, San Diego, Calif.

Application January 18, 1946, Serial No. 642,026

1 Claim. (Cl. 74—6)

1

This invention relates to a starter unit for a power scooter and more particularly to an electrical starter, the primary object of which is to eliminate the mechanical ratchet kick starter in use at the present time.

The unit starts any scooter in approximately ten seconds. It also eliminates the possibilities of a kick-back thereby injuring the operator thereof. Any person who is partially disabled can start a scooter equipped with this type of starter unit. Whereas with the kick type of starter a person handicapped physically could not enjoy a scooter.

Another object of the invention is to provide a starter unit that is simple in operation, durable in use and can be easily installed on a scooter.

With the above and other objects and advantages in view the invention consists of the novel details of construction, arrangement and combination of parts more fully hereinafter described, claimed and illustrated in the accompanying drawings in which:

Figure 1 is a side view of the starter unit as installed on a scooter;

Fig. 2 is a top plan view partly in section and partly broken away to more clearly show the drive connection of the scooter and its associations with the starter unit.

Referring to the drawings in detail, the reference numeral 10 designates a standard electrical starter which is mounted on by means of fasteners 12 to the upper end of a vertical angle bar support 14, the lower end of which is secured to the frame 16 of the scooter 18 by welding or any other well known means 19.

Mounted on the support 14 by means of fasteners 20 in a position below the starter 10 is the standard solenoid starter switch 22, having one lead 24 thereof connected to the starter 10 in the usual manner, the other lead 26 being connected to a storage battery 28 secured to the frame 16 of the scooter 18 at some convenient location, and the battery is provided with the usual ground connection not shown.

The starter 10 is provided with a V-pulley 30 on the drive shaft 32 thereof which is connected to the V-pulley 34 on the drive shaft 36 of the internal combustion engine A for the scooter 18 by the V-belt 38. The drive shaft 36 is connected to the motor drive shaft by the coupling 37. The drive shaft 36 has the member 33 of the clutch mechanism 39 fixed thereto and this member is adapted to coact with the freely running member 35. The clutch mechanism being of the

centrifugal type so that the increase in speed of the shaft 36 will cause the clutch mechanism to operate. The pulley 34 has the usual fasteners 40 connected to the drive shaft 36. To prevent dis-
5 placement the fasteners 40 are connected by the wire 42 and a belt drive 43 engaging a pulley 41 on the drive shaft 36 is trained over the pulley 45 mounted on the shaft 43 of the generator to cause rotation of the generator 44 shown in Figure 1.
10 The generator being mounted on the motor A of the scooter 18 and the chain drive 46 from the clutch on the clutch drive sprocket 45 on the member 35 of the clutch mechanism 39 is trained over the sprocket drive wheel 48 on the rear wheel 50 whereby rotary motion may be transmitted to the rear wheel 50 of the scooter 18.

Pivotedly connected to the lower end of the support 14 by means of a bolt 52 having the bushing 53 thereon is the foot actuating lever 54 having the pedal knob 56 on the free end thereof.

The lever 54 mounts the rubber block 58 by means of the bolt 60 and a contact bolt 62 mounted in the rubber block 58 is connected to the switch 22 by the primary lead 64.

25 Pivotedly connected to the lever 54 forwardly of the block 58 by means of the bolt 65 is the lower end of the connecting link 66, the upper end of which is pivotally connected to belt tensioning levers 68 by the bolt 70. The levers 68 are formed in parallel relation to each other by bolts 70 and 72 on which are mounted the roller bearings 74 and a third bolt 76 having a bushing 77 thereon, intermediate the levers 68 is adapted to pivotally connect the levers to the support 14, 30 a bushing on the bolt intermediate the levers and support properly positioning the levers with relation to the support.

The belt 38 passes intermediately of the rollers 74 so that when the lever 54 is depressed the belt 40 will be tightened causing the rotation of the drive shaft 36 by the starter at the same time the lever 54 is depressed the bolt 62 makes contact with the frame thus energizing the starter.

A spring 80 connected at one end to the lever 45 54 and at the other end to the support 14 tensions the lever 54 to keep it in raised inoperative position at all times except when depressed by the foot at which time the spring will return the lever to inoperative position upon release of the 50 foot from the lever.

This assembly when mounted on the scooter requires moving the gas tank of the scooter and the reassembling thereof in the forward luggage compartment and adding an additional length of 55 fuel line. The right side of the scooter cowling

will also have to be reformed to accommodate the unit.

As previously stated the operation of the unit is caused by depressing the lever 54, causing the contact bolt to complete the circuit through the starter frame and tensioning the belt to cause rotation of the drive shaft 36 by the starter. After the motor has started increase in the rotation thereof will cause the clutch members 33 and 35 to engage to cause the rotation of the wheel 50 and subsequent driving of the scooter in the usual manner.

It is believed that the operation and construction of the unit will be apparent to those skilled in the art and it is to be understood that changes in the details of construction, arrangement and combination of parts may be resorted to providing they fall within the spirit of the invention and the scope of the appended claim.

Having thus described the invention what is claimed as new and desired to be secured by Letters Patent is:

A device of the character described, comprising a support, an electrical starter mounted on said support, a switch on said support for energizing said starter, current means for said starter, a belt drive for connecting said starter to a driven means, manually actuated means for tensioning said belt drive to cause rotation of said driven

25

means by said starter, said last means comprising a pair of spaced upper levers and a lower lever pivotally connected at their inner ends to said support in spaced relation to each other, a link connected at its lower end to the lower lever and at its upper end to the upper levers, a roller rotatably mounted intermediate of the upper parallel levers at their outer ends, a second roller rotatably mounted intermediate of the upper levers at the point of connection of the link with the upper levers, and said rollers are mounted for coaction with said belt drive, a pedal connected to the outer end of said lower lever whereby pressure of said pedal causes said rollers to engage and tension said belt drive and spring means connected to said lower lever and said support to return said lower lever upwardly after the depression thereof.
